ARTHUR J. BAZELEY, OF CLEVELAND, OHIO, ASSIGNOR TO THE NATIONAL MALLEABLE CASTINGS COMPANY, OF CLEVELAND, OHIO, A CORPORATION OF OHIO.

CAR-COUPING.

1,204,119.

Specification of Letters Patent.

Patented Nov. 7, 1916.

Application filed December 27, 1915. Serial No. 68,668.

To all whom it may concern:

Be it known that I, ARTHUR J. BAZELEY, a citizen of the United States, residing at Cleveland, Cuyahoga county, Ohio, have invented new and useful Improvements in Car-Couplings, of which the following is a specification, reference being had to the accompanying drawings, in which—

Figure 1 is a section of a car coupler embodying my invention; Fig. 2 is a plan thereof; Fig. 3 is an elevation of the lock lifter; Fig. 4 is a plan of the lifter, and Figs. 5 and 6 are sections on lines V—V and VI—VI respectively of Fig. 3.

15 My invention relates to car couplers and particularly to the lock lifting mechanism therefor.

I have found in certain types of couplers now in use, that through carelessness of 20 workmen the lifter is sometimes applied in reversed position with the result that while the lock may be lifted, the coupler is usually rendered inoperative.

The object of the present invention is to 25 prevent such occurrences and to this end I have designed the lifter and coupler head so that the lifter can be applied to the coupler head and the lock only in the proper position and relation.

30 My invention also relates to the construction and coöperation of the various parts which I shall hereinafter describe and claim.

Referring to the drawings, in which I have 35 shown a coupler of the type shown in my Patent No. 1,144,315, dated June 22, 1915, A indicates the coupler head, B the knuckle, C the lock, D the opener, and E the lifter. At its lower end the lifter E has trunnions 2 which seat in recesses 3 on the rear side of 40 the lock C and by which engagement the lock is supported and operated. On its rear side the lifter has also angled faces 4 and 5 which coöperate with corresponding 45 faces on the projection 6 at the rear of the coupler cavity and serve not only to prevent the trunnions from disengaging from the recesses in the lock but also act as an anti- 50 creep or down hold for the lock. To insure the proper coöperation between the lifter and the lock and the lifter and the anti-

creep projection 6, the lifter E near its upper end is made of wedge shape in cross section, as shown in Fig. 2 and operates in the correspondingly shaped top hole or lifter 55 opening 7 of the coupler head. As is shown in Fig. 5 the lifter at its rear side has a web 8 which in the upper portion is wider than the web 9 at its forward side. It will therefore be seen that the lifter cannot be inserted into 60 the coupler head in reversed position since its rear side is too wide to pass through the small forward extremity of the lifter opening 7.

The terms and expressions which I have 65 employed are used as terms of description and not of limitation, and I have no intention, in the use of such terms and expressions, of excluding any mechanical equivalent for the features shown and described, 70 but recognize that various modifications are possible within the scope of the invention claimed.

What I claim is:

1. In a car coupler, a lock and a lock-lifter, 75 the lifter being capable of engagement with the lock in two positions only one of which is an operative position, and a coupler-head having a wedge shaped lifter opening, the shank of the lifter being also wedge shaped 80 to conform to the lifter opening and permitting the application of the lifter to the lock in operative position only.

2. In a car coupler, a coupler head, a lock, and a lock-lifter, said lifter having trunnions at its lower end and faces at the rear side of said lower end adapted to coöperate with the coupler head when the lifter is in normal relation with the lock and the lock is in lowermost position to act as a down hold 90 for the lock, a slot in the lock, adapted to receive said lifter trunnions, said lifter being capable of engagement with said lock in two diametrically opposite positions, only one of which is an operative position, the coupler 95 head having an aperture of non-symmetrical cross section corresponding to the cross sectional shape of the lifter at its upper end, and being thereby adapted to permit the engagement of the lifter and the lock in operative position only.

ARTHUR J. BAZELEY.
